UNITED STATES PATENT OFFICE.

ERASmus D. LEAVITT, JR., OF CAMBRIDGEPORT, MASSACHUSETTS.

HOISTING-ENGINE.

SPECIFICATION forming part of Letters Patent No. 402,257, dated April 30, 1889.

Application filed October 12, 1888. Serial No. 287,953. (No model.)

To all whom it may concern:

Be it known that I, ERASmus D. LEAVITT, Jr., of Cambridgeport, in the county of Middlesex and State of Massachusetts, have invented certain new and useful Improvements in Hoisting-Engines, of which the following, taken in connection with the accompanying drawings, is a specification.

In mining communities where steam hoisting-engines are used for the purpose of raising ore from the mines it is frequently found desirable to transmit to the hoisting-drum an intermittent motion which shall be entirely independent of any motion which may be transmitted from the main engine; and it is to accomplish this result which is the object of this invention, which consists in certain novel features of construction, arrangement, and combination of parts, which will be readily understood by reference to the description of the drawings and to the claims to be hereinafter given.

Of the drawings, Figure 1 represents an elevation of my improved device for imparting to the hoisting-drum an intermittent rotary motion and showing said drum cut in section. Fig. 2 represents a central vertical longitudinal sectional elevation of the fleet-ing-engine of said device. Fig. 3 represents a similar sectional elevation of the fleet-ing-strap cross-head and its bed-plate, the fleet-ing-strap ends and their connections with said cross-head being shown in elevation. Fig. 4 represents a transverse sectional elevation of the fleet-ing-engine cylinder, the cutting-plane being on line 11 on Fig. 2. Fig. 5 represents a central longitudinal sectional elevation of the fleet-ing-engine cross-head. Fig. 6 represents an end elevation of the same, the ends of the side bars and a portion of the trunnion-block being shown in section in order to more clearly illustrate the method of connecting said cross-head to the fleet-ing-cylinder piston-rod. Fig. 7 represents a transverse sectional elevation of the same, the cutting-plane being on line 22 on Fig. 5. Fig. 8 represents a transverse sectional elevation of the same, the cutting-plane being on line 33 on Fig. 5. Fig. 9 represents a sectional elevation of a portion of one of the sliding pipes and its packing. Fig. 10 represents a transverse sectional elevation of the fleet-ing-strap cross-head. Fig. 11 rep-

resents a section of the guide for the fleet-ing-engine cross-head. Fig. 12 represents a section of the guide for the fleet-ing-strap cross-head. Figs. 13 and 14 represent details of the fleet-ing-strap end connections. Figs. 15, 16, and 17 represent, respectively, a rear elevation, a side elevation, and a front elevation of the hydraulic valve-gear. Fig. 18 represents a sectional elevation of the valve stand and chest, the cutting-plane being on line 44 on Fig. 20. Fig. 19 represents a horizontal section of the same, the cutting-plane being on line 55 on Fig. 20. Fig. 20 represents a front elevation of the upper portion of the valve-stand. Fig. 21 represents a sectional elevation, the cutting-plane being on line 66 on Fig. 16.

In the drawings, A is the bed-plate, upon which is secured the cylinder B, in which is mounted the piston B', to which is attached the piston-rod B², the outer end of which is fastened securely to the trunnion-block C by means of the key a, which block C is provided with the trunnions a' a', extending from opposite sides thereof into suitable bearings in the side bars, C' C', of the fleet-ing-engine cross-head. The side bars, C' C', are secured together by the transverse bars C² C², the ends of which project beyond said side bars, C' C', into the open slots a² a², formed in the guides C³, so that said frame C' C' C² C² may be reciprocated back and forth therein as the piston B is reciprocated within the cylinder A.

To the side bars, C' C', and above the transverse bars C² C², are secured the two cylinders D and D', the former of which is somewhat larger than the other in diameter. The ends of these cylinders which are toward each other are provided with suitable openings to receive the plunger D², which is adapted to reciprocate within said cylinders, which are securely tied together at their upper sides by the tie-rod b.

To the plunger D² is pivoted at b' the link b², to the free end of which is pivoted the upper end of the lever E, which is mounted upon the fulcrum-pin c, secured in the side bars, C' C', and which extends beyond said fulcrum-pin c, and has pivoted to its lower end one end of the connecting-rod F, the opposite end of which is pivoted to the lower

end of the lever F' , which is mounted upon the fulcrum-pin d , secured in the cross-head G , which is provided with laterally-projecting lips d' , which extend into the grooves d^2 , formed in the guides G' upon either side of said cross-head G .

The fulcrum-pin c is connected to the fulcrum-pin d by means of the rod H , so that the cross-head G will reciprocate whenever the side-bars, $C' C'$, with the pin c , are reciprocated; but the grooves d^2 are made curved and concentric to the axis of the hoisting-drum, which is located immediately above the center of said guides G' , as shown in Fig. 1, so that when said cross-head G is reciprocated it will always remain the same distance from the axis of the shaft I , upon which the hoisting-drum is mounted, only that portion of which is shown in the drawings which is known as the "brake-wheel" J , which forms a part of, and conforms to all the motions of the hoisting-drum.

To the upper end of the lever F' is pivoted the link J' , the opposite end of which is pivoted to the casting J^2 , secured to one end of the steel strap K in any well-known manner. The steel strap K passes nearly around the brake-wheel J , and has secured to its other end another similar casting or end piece, K' , to which is pivoted in a well-known manner the threaded bolt K^2 , upon which is adjustably mounted the stirrup K^3 , secured to the fulcrum-pin d .

The outer ends of the cylinders D and D' are provided, respectively, with the nozzles D^3 and D^4 , into which the pipes L and L' are secured, so that they will reciprocate with the cylinders D and D' , the other ends of said pipes extending, respectively, into the cylindrical water-chambers M and M' , formed in a suitable casting secured above said cylinder B .

The joints where the pipes L and L' pass into the said chambers M and M' may be packed in any well-known manner; but I prefer the packing shown in Fig. 9, in which e is a composition bushing, e' is the leather packing, and e^2 is a nut to crowd the packing into place.

To the platform N , located above the fleeting-engine, is secured the stand N' , to the front side of which is secured the valve-chest N^2 , in which are mounted the vertical valve-stems $g g$, which operate the valves $g' g'$ to open and close the ports in a well-known manner.

The inlet-pipe h communicates directly with the interior of the valve-chest N^2 , while the exhaust-pipe h' communicates with the chamber h^2 in the stand N' , which chamber h^2 is provided with the ports $h^3 h^3$, which communicate with the interior of the valve-chest and are continually covered by the valves $g' g'$, so that the inlet-water is prevented from passing through the same without first passing through the fleeting-engine. Above the left-hand port h^3 , Figs. 19 and 20, is a port, i ,

which communicates through the pipe i' with the back or left-hand end of the fleeting-engine cylinder, while below said port h^3 is another similar port, i' , which communicates through the pipe i^3 with the front or right-hand end of said cylinder.

Above the right-hand port h^3 is a port, k , which communicates through the pipe k' with the chamber M' , which in turn communicates through the pipe L' and nozzle D^4 with the interior of the small clamp-cylinder D' , while beneath said port h^3 is located a similar port, k^2 , which communicates through the pipe k^3 with the chamber M , from which the water may pass through the pipe L and nozzle D^3 to the cylinder D .

Each of the valve-stems $g g$ is connected at its lower end by means of the links $l l$ to the inner end of the lever l' , which is pivoted at l^2 to the cross-head l^3 , and the opposite end of which is connected by the link l^4 to the end of the lever l^5 , secured upon one end of the shaft l^6 , which is mounted in the stand l^7 , and has secured to its opposite end the hand-lever O , by which the valve may be operated to direct the water through the upper or lower port, as desired, all in a well-known manner.

The cross-head l^3 is mounted in the guide m , Figs. 16 and 21, which is secured to the platform N , while to the lower end of said cross-head is secured the upper end of the link m' , the opposite end of which is mounted upon the pin m^2 , secured to the enlarged end of the link-shaft m^3 at a short distance from the center of said shaft m^3 , which is mounted in a bearing in the bracket m^4 , and has secured to its other end the lever n , the outer end of which is connected by the rod n' to the pantograph P , of the usual construction, which is hung from the bracket o , secured to the under side of the platform N , and which has its free end connected to the cylinder D , so that all motion of said cylinder will be transmitted through said pantograph to said connecting-rod n' , the amount of movement, however, of said rod n' being greatly reduced as compared with the movement of said cylinder.

The operation of my invention is as follows: The right-hand lever O is first moved toward the frame N , (see Fig. 1,) thus raising the valve g' , so that the water may pass from the inlet-pipe h to the interior of the valve-chest N^2 and from this chamber through the lower port, k^2 , to the pipe k^3 , through which it is carried to the chamber M , from which it passes through the pipe L and nozzle D^3 into the interior of the cylinder D , thus forcing the plunger D^2 toward the brake-wheel J , and moving the lever E about its fulcrum-pin c , and causing the connecting-rod F to move toward the fleeting-engine cylinder, which movement of the rod F is transmitted to the lever F' , causing the same to move about its fulcrum d , so that the ends of the fleeting-strap K will be brought nearer together, thus securely clamping said wheel J in an obvious

manner. While the inlet-water is passing into the cylinder D, the water in the cylinder D' will be forced out by the plunger D², said water passing through the nozzle D⁴ and pipe L' into the chamber M', from which it passes through the pipe k' to the port k, along the valve g' to the port h³ into the chamber h² in the stand N', from which it is carried away by the exhaust-pipe h'. The wheel J being 5 securely clamped by the strap K, the left-hand lever O is moved toward the frame N, thereby moving the valve g', so as to uncover the port i², so that the water may pass through the same to the pipe i³, through which it is 10 carried to the front or right-hand end of the fleeting-engine cylinder. While the cylinder B is being thus filled, the piston B' is being moved to the left or away from the brake-wheel J by the action thereon of the water 15 being admitted to said cylinder from the pipe i³. As the piston B' moves toward the left-hand end of the cylinder, the water contained in that end is forced out through the pipe i' to the port i, through which it passes along 20 the valve g' to the port h³ and the chamber h², from which the water is carried away by the exhaust-pipe h'. The piston B' being connected by the piston-rod B² to the side bars, C' C', upon which the cylinders D and 25 D' are mounted, it is obvious that said cylinders, the pipes L and L', and the pin c, mounted in the side bars, C' C', will all conform to the reciprocating movements of the piston B', and since the pin c is connected by 30 the rod H to the pin d, mounted in the cross-head G, said cross-head G will also be reciprocated by the action of the water upon the piston B'; but by virtue of the curvature of the guides G' G', in which said cross-head G 35 is mounted, said cross-head will of necessity travel in a path concentric with the axis of the shaft I, so that the fulcrum-pin d will at all times remain the same distance from the rim of the wheel J. When said strap K is 40 clamped to said wheel J and said cross-head G is moved toward the cylinder B, it is obvious that said wheel J will be moved about its axis a distance equal or nearly equal to the stroke of the piston B' within the cylinder B. 45 The movement of the cylinder D away from the drum causes its motion to be transmitted through the pantograph P to the rod n', which in turn operates the lever n, which turns in its bearing the shaft m³, so that the pin m² 50 will be lowered, which motion will be transmitted through the link m' to the cross-head l³, causing the same to assume a lower position. As the upper end of said cross-head l³ is pivoted to the lever l' at l², said lever l' is 55 made to swing about the joint p, so that the free end of said lever l' is lowered sufficiently to cause the valve g' to cover both the ports i and i², when no more water can be transmitted to either end of the fleeting-engine cylinder, and consequently the movement of the piston B' and the parts secured thereto 60 will cease, and as said cylinder is filled with 65 water upon either side of said piston it will be locked, so that it cannot move in either direction. The length of stroke of said piston, and consequently the amount of movement of said wheel J, may be predetermined by the movement of the lever O. For instance, supposing the piston B' is at the right-hand end of the cylinder B and it is desired 70 to move it into the position in which it is shown in the drawings, the operator will move the right-hand lever O sufficiently to clamp the wheel J, and then he will move the left-hand lever O into the position in which it is 75 shown in Fig. 16, and in which position it will be locked to the frame r' by the locking device r, which may be of any well-known construction. As has already been described, the water will pass through the pipe i³ to the 80 front end of the cylinder B, causing the piston B' to move away from the drum; but as soon as the cylinder D has moved into the position shown in the drawings its motion 85 will have been transmitted through the automatic stopping device to cause the cross-head to be lowered and operate the lever l' and the valve g', so that they will assume the positions shown in the drawings, when the movement of said piston B' will cease, as has already been described. This is accomplished 90 by virtue of the fact that as soon as the cylinder D begins to move toward the cylinder B or away from the drum the cross-head l³ and valve g' will begin to be lowered, and if 95 the valve g' is in one case only moved by the lever O a short distance, so that it but partially uncovers the port i², while in another case said valve is moved far enough to entirely uncover said port i², it follows that the 100 valve g' in the first instance, having a shorter distance to travel, will cover both ports i and i² sooner than it would cover the same ports in the latter case, where the valve must travel a longer distance before the water is cut off 105 from passing to the cylinder B. By virtue of this fact it is obvious that any length of stroke of the piston B' may readily be determined, and if it is desired that the piston should travel the entire length of the cylinder B the operating-lever is moved as far to the rear as possible, which will cause the valve g' to be moved upward as far as it can go, so that the said valve will not be able to 110 again cover both the ports i and i² until the 115 piston B' has moved to the rear end of the cylinder B.

In order to release the wheel J and move the parts back to their former positions preparatory to another grip-and-pull operation, 120 the operator moves the right-hand lever toward the left-hand side of Fig. 16, thus uncovering the upper port, k, and allowing the inlet-water to pass through the same into the pipe k', through which it will be carried to 125 the chamber M', and thence through the pipe L' and nozzle D⁴ to the interior of the cylinder D', thus forcing the plunger D² toward the cylinder D and releasing the clamp of 130

the strap K upon the wheel J, the water in the cylinder D being forced out through the pipe I, the chamber M, the pipe k^3 , the port k^2 , along the valve g' to the port i^3 , into the chamber i^2 , and away by the exhaust-pipe h' . The operator will then move the left-hand lever toward the left side of Fig. 16, thus lowering the valve g' , so as to uncover the port i , so that the inlet-water may pass through the same into the pipe i' , by which it is conveyed to the back end of the cylinder B, thus forcing the piston B' toward the drum, and with said piston the cylinders D and D', which movement will operate the pantograph P, the connecting-rod n' , the lever n , the shaft m^3 , the link m , and the cross-head l' to again raise the end of the lever l' and the valve g' , so that said valve will again cover both of the ports i and i^2 . It is obvious that in this operation the strap K will be simply slipped around the wheel J without moving it about its axis.

It is evident that by clamping the wheel J and allowing the cylinder B to remain filled with water, with the valve g' over the ports i and i^2 , this device may be used as a brake.

With the foregoing it is believed that the operation of my invention will be readily understood without further description, while its advantages are obvious.

What I claim as new, and desire to secure by Letters Patent of the United States, is—

1. In combination with the brake-wheel of a hoisting-drum, a reciprocating cross-head, a lever pivoted to said cross-head, a strap encircling said wheel and connected at one end to said cross-head and at the other end with one end of said lever, and means for moving said lever in one direction to clamp said strap to said wheel, so that said wheel will move about its axis with said cross-head and in the opposite direction to loosen the grip of said strap upon said wheel.

2. In combination with the brake-wheel of a hoisting-drum, a cross-head reciprocating in a path concentric with the axis of said wheel, a fulcrum-pin mounted in said cross-head, a lever mounted upon said pin, a strap encircling said wheel and connected at one end to said cross-head and at the other end with one end of said lever, a reciprocating frame, a lever pivoted to said frame, a rod connecting the lower ends of said levers, another rod connecting said cross-head and said sliding frame, two cylinders secured to said reciprocating frame, and a reciprocating plunger mounted in said cylinders and connected with the upper end of the lever pivoted to said reciprocating frame.

3. In combination with the brake-wheel of a hoisting-drum, a fixed cylinder, a reciprocating piston mounted within said cylinder, a cross head or frame mounted in suitable guides, a rod connecting said cross-head with said piston, a lever mounted upon said cross-head, an engine-cylinder mounted upon and

movable with said cross head or frame, a piston fitted to said cylinder and arranged to be reciprocated therein and connected to one end of said lever, a second cross-head mounted in guides located beneath said brake-wheel and curved to an arc of a circle concentric to the axis thereof, a rod connecting said two cross-heads, a lever pivoted at or near the center of its length to said second cross-head, a brake-strap surrounding said brake-wheel and connected at one end to said second cross-head and at its other end to one end of the lever carried by said cross-head, and a rod connecting the other end of said lever with the lever pivoted to the first-mentioned cross head or frame.

4. In combination with a fixed cylinder, a piston reciprocating in said cylinder, a frame adapted to slide in suitable guides, a rod connecting said piston with said frame, two cylinders secured to said frame in axial line with each other, a plunger mounted in said cylinders and extending from one to the other, a casting secured to said fixed cylinder and provided with two parallel water-chambers, a pipe secured to one of said sliding cylinders and extending into one of said water-chambers, another pipe secured to the other sliding cylinder and extending into the other water-chamber, and pipes leading to the outer ends of said water-chambers to admit the water thereto or exhaust it therefrom, as the case may be, valves for controlling the flow of water to or from said water-chambers, a two-armed lever pivoted to said reciprocating frame and connected at one end to said plunger, a brake-wheel, a second cross-head located beneath said brake-wheel, curved slides for guiding said second cross-head in a path concentric to the axis of said brake-wheel, a second two-armed lever pivoted to said second cross-head, a brake-strap surrounding said brake-wheel, a rod connecting said reciprocating frame and second cross-head, and a rod connecting the lower ends of the two two-armed levers.

5. In combination with the brake-wheel of a hoisting-drum, a cross-head reciprocating in a path concentric with the axis of said wheel, a fulcrum-pin mounted in said cross-head, a lever mounted upon said pin, a strap encircling said wheel and connected at one end to said cross-head and at the other end with one end of said lever, a reciprocating cross head or frame, a lever pivoted to said frame, a rod connecting the lower ends of said levers, another rod connecting said cross-head and said reciprocating frame, two cylinders secured to said reciprocating frame in axial line with each other, a reciprocating plunger mounted in said cylinders and extending from one to the other and connected to the upper end of the lever pivoted to said reciprocating frame, a fixed cylinder, a piston mounted in said fixed cylinder and adapted to reciprocate therein, and a rod connecting said piston to

said reciprocating frame, so that said frame, said cross-head, and said piston will all move in unison.

6. In combination with the brake-wheel of 5 a hoisting-drum, a reciprocating frame, two cylinders secured to said frame in axial line with each other, a plunger mounted in said cylinders and extending from one to the other, a lever pivoted to said reciprocating frame and connected at one end to said plunger, and pipes connecting with the outer ends of said cylinders to admit water to reciprocate said plunger, a cross-head located beneath said brake-wheel and arranged to be reciprocated in a path concentric to the axis of said wheel, a two-armed lever pivoted to said cross-head, a brake-strap surrounding said brake-wheel and pivoted at one end to said cross-head and at its other end to one end of 15 the lever carried by said cross-head, and a rod connecting the other end of said lever with the lower end of the two-armed lever carried by said reciprocating frame.

7. In combination with the brake-wheel of 25 a hoisting-drum, a reciprocating frame, a cylinder and piston for transmitting motion to said reciprocating frame, a valve-seat provided with an exhaust-port and another port upon either side of said exhaust-port, pipes 30 connecting said outer ports with the opposite ends of said cylinder, a valve adapted to cover all of said ports or either two of them, as desired, a valve-stem for operating said valve, a lever connected at one end to said 35 valve-stem and at the other end to a fulcrum-pin which is adapted to be raised or lowered at the will of the operator, a sliding cross-head pivoted at one end to said lever, and a series of links and levers interposed between 40 said reciprocating frame and said cross-head, by which, when said frame is moved away from the hoisting-drum, said cross-head will be moved so that all the ports in the valve-seat will be closed by said valve.

45 8. In combination with the brake-wheel of a hoisting-engine and a gripping or clamping device constructed and arranged to be intermittently clamped to and released from said wheel, a fixed cylinder, a piston working 50 in said cylinder, a reciprocating frame or cross-head connected by a piston-rod to said piston, a pair of differential cylinders mounted upon and movable with said frame, a differential plunger fitted to said cylinders and 55 extending from one to the other, a lever mounted on said frame and connected at one end to said differential plunger and at its other end to the gripping device, a pair of fixed water-chambers, pipes leading from the 60 interior of said water-chambers to the opposite ends of said differential cylinders, a valve-chamber provided with two sets of ports leading therefrom and two valves to cover said ports, pipes leading from the two outer ports 65 of one set to the opposite ends of the fixed cylinder, pipes leading from the two outer ports of the other set to the interior of the

water-chambers, a cross-head connected at one end with the stem of the valve that controls the flow of water to the fixed cylinder, 70 and a system of links and rods connecting the other end of said cross-head to one of said differential cylinders or to the frame on which said cylinder is mounted.

9. The combination of the fixed cylinder B, 75 the piston B', the piston-rod B², a reciprocating cross head or frame connected to said piston-rod, the differential cylinders D and D', mounted upon and movable with said reciprocating frame, a differential plunger fitted 80 to said differential cylinders and extending from one to the other, the fixed water-chambers M and M', the pipes L and L', the valve-chamber N², the two valves g' g', the ports i, i², h³, h³, k, and k², pipes connecting ports i 85 and i² with the opposite ends of the cylinder B, pipes connecting the ports k and k² with the water-chambers M' and M, respectively, the valve-rods g g, hand-levers O, means for locking one of said levers in any desired position, 90 links l and l⁴, levers l' and l⁵, the cross-head l³, the pantograph P, the crank-shaft m³, lever n, and rod n', all constructed, arranged, and operating substantially as described.

10. In combination with the brake-wheel of 95 a hoisting-drum, a reciprocating cross-head, a strap encircling said wheel and secured at one end to said cross-head, a frame reciprocating in unison with said cross-head, a lever for causing said strap to grip the said wheel when said cross-head is at one end of its movement and to release the same when at the other end of its movement, a pair of differential cylinders mounted upon and movable with said frame, a differential plunger fitted to said cylinders 100 105 and extending from one to the other, a two-armed lever pivoted to said frame and connected at its upper end to said plunger, a rod connecting the other end of said lever to the strap-clamping lever, a valve-seat provided with three ports in line with each other, a fixed cylinder, a piston adapted to reciprocate within said cylinder and connected with said frame, pipes connecting the ends of said cylinder with two of the ports in said valve-seat, a lever for operating said valve to uncover either of the outer ports and allow water to pass into either end of said cylinder and cause the piston, frame, and cross-head to be moved toward or from said drum, as may 110 115 be desired, and a system of links and levers connecting said reciprocating frame with the valve, and so arranged that it will cause said valve to cover said ports when said frame has moved a predetermined distance and prevent all further movement in that direction.

In testimony whereof I have signed my name to this specification, in the presence of two subscribing witnesses, on this 8th day of October, A. D. 1888.
